SAFETY RAZOR AND MAGAZINE

Joseph Muros, Cambridge, Mass., assignor to Gillette Safety Razor Company, Boston, Mass., a corporation of Delaware

Application April 7, 1943, Serial No. 482,109

8 Claims. (Cl. 30—40)

This invention relates to safety razors and consists in a novel combination of safety razor and blade magazine wherein these two elements are locked together against separation or displacement during the operation of feeding a blade from the magazine to the razor.

The present invention may be advantageously applied to any safety razor provided with a blade seat or a blade holder whereon or wherein the blade is held accurately in position for shaving by clamping or positioning means which are arranged to be retracted to permit removal of a used blade or delivery of a fresh blade. The blade magazines used with such razors are usually equipped with a projecting finger or key adapted to be inserted in the razor head for the purpose of aligning the outlet of the magazine with the blade seat and in some cases also for retracting the blade-clamping means so that a fresh blade in reaching its final shaving position in the razor may contact and push the used blade out of the razor.

In razor-magazine combinations heretofore available it has frequently happened that, in advancing a blade from the magazine, the magazine itself is accidentally pulled back or allowed to become displaced rearwardly in respect to direction of the blade feeding movement with the result that the fresh blade is not advanced fully into its shaving position but remains with a portion of its length projecting somewhat from the razor when the magazine is removed. This, of course, constitutes a serious hazard for the user. The danger of premature separation of the razor and magazine in the manner described is intensified when the magazine is equipped with a feed slide because of the tendency of the user to move his fingers holding the magazine in the opposite direction to the fingers moving the feed slide in delivering a blade to the razor.

My prior application, Serial Number 481,260, filed March 31, 1943, discloses a mechanism for locking a safety razor and magazine against separation through the medium of the key, the razor being provided with a releasing device which must be operated by the user for that purpose alone. The present invention in one aspect consists in a new and improved locking device arranged to operate independently of the key and to be released as part of the usual blade-delivering cycle, as for example, by movement of the feed slide upon the magazine into blade-delivering position.

Objects of the invention are to provide simple and compact means for automatically locking

the razor and magazine together when they are assembled for blade delivery. Preferably and as herein shown these two elements remain positively interlocked until released by movement of the feed slide in the final portion of its blade-delivering movement. The user must operate the feed slide to advance a fresh blade from the stack in the magazine into its shaving position in the razor head and it is only when this movement of the feed slide has been completed and the entire length of the blade sheathed in the razor head that the feed slide becomes effective to release the locking means which permit separation of the magazine.

These and other features of the invention will be best understood and appreciated from the following description of a preferred embodiment thereof selected for purposes of illustration and shown in the accompanying drawing, in which:

Fig. 1 is a view in perspective on an enlarged scale of the safety razor head, the key of the magazine being shown in dotted lines and a portion of one upright being broken away;

Fig. 2 is a similar view in perspective of the razor head showing a portion of the magazine in blade-delivering position; and

Fig. 3 is a fragmentary view of the same part showing the locking device in retracted position.

The invention is herein shown in its application to a safety razor of the stropping type of the general character described in my prior application Serial Number 477,239, filed February 26, 1943, although the invention is in no sense limited to that or to any specific type of safety razor.

The illustrated razor includes in its structure a solid handle 10 from the upper end of which projects a square tubular shank 11. This is provided at its upper end with out-turned transverse ears 12 through the medium of which the razor head is attached to the handle. The front and rear walls of the shank 11 are cut out, as shown in detail in my said application above identified, to form the lower part of a forwardly and downwardly inclined guideway. The upper portion of the guideway is formed by a similarly inclined plate having side walls which merge into transverse ears 13 similar in outline to the ears 12 of the shank and arranged in superposed position above them. In the guideway formed in the walls of the shank slides the body 20 of a blade-clamping device which will be presently described.

Above the ears 13 is located the bottom plate 14 of the head frame of the razor and this is provided at opposite sides with upright side members 15. These side members are roughly tri-

angular in shape, tapering downwardly and forwardly. Between them extend three transverse shafts which stiffen the frame and guide the strop. Of these the uppermost shaft 16 carries a hollow sleeve 29 which is extended forwardly into the upper and lower clamping plates of the blade holder. The blade projects beyond these plates and rests upon the blade seat 40 shown in part in Fig. 1 but more fully described in my co-pending application above identified to which reference may be had for complete details of the blade seat and blade holder.

Next above the base plate 14 comes a stationary sheet metal member in which is formed the guard 19. The blade seat 40 is formed by an inner portion of this member. In one side member 15 is formed a substantially rectangular notch 17 providing a passage into the interior of the razor head for the magazine key 38 which, as suggested in Fig. 1, may be entered through this passage in approximately horizontal position and which locates the magazine properly in position to deliver fresh blades one at a time to the blade holder. The side member 15 is also provided with a square aperture 18 for receiving a pilot spur on the magazine.

The movable element of the razor comprises a blade-clamping device for holding the blade securely in shaving position on the blade seat. The body of this device has already been referred to as the slide 20 arranged to move freely in an inclined guideway formed in the shank of the razor. At its rear end the slide merges into a downturned finger piece 21 by which the device may be retracted. At its forward end the slide 20 merges into an upstanding vertical wall 22 fitting into and substantially filling the portion cut-out from the front wall of the shank 11. The vertical wall 22 merges at its upper end into a downwardly and forwardly inclined portion 23 having a square aperture 28 therein. The portion 23 in turn merges into a hooked portion 24 extending upwardly and rearwardly in spaced relation to the portion 23. The portions 23 and 24 together with an internal edge or surface inside the razor head constitute a guideway for the reception of the key 38 of the magazine which is shown in dotted lines in Fig. 1. The hooked portion 24 is centrally disposed in the clamping device, as shown in Fig. 1, and at each end thereof is provided an upwardly and forwardly extending arm 25. The arms are curved rearwardly above the blade seat and support a transverse blade-clamping bar 26 at its opposite ends. Both of the upstanding arms 25 are provided with rearwardly or inwardly extending guide arms 27 which slide against the end edges of the stationary guard. Within the shank 11 is provided a torsion spring connected to the slide 20 of the blade-clamping device and tending at all times to move it rearwardly, that is to say, into the blade-clamping position shown in Fig. 1.

The magazine herein shown is generally rectangular in shape and designed to hold a stack of ten or twelve blades which are to be delivered one by one through a slot in the left end of the magazine as seen in Figs. 2 and 3. The bottom plate 30 of the magazine is extended forwardly to provide a key 38 and this key is shaped to enter the passage 17 in the razor and to retract the blade-clamping device 20-25. The key 38 projects from the left-hand end of the magazine which is concealed in the views of the drawing. The magazine is also provided with a square pilot spur constructed and arranged to enter the square

aperture 18 in the upright side member 15 of the razor head and thus to assist the key in properly locating the magazine and prevent it from twisting on the key. As shown in Fig. 2 a flat leaf spring 32 underlies the stack of blades 31 and holds the uppermost blade in the stack yieldingly against the roof of the magazine. A feed slide 33 is arranged to reciprocate upon the magazine and is provided with an internal extension for engaging the uppermost blade of the stack and advancing it to and through the outlet slot of the magazine.

To the bottom of the magazine is attached by means of a rivet 35 a sheet metal member 34. This has an upstanding flange portion 36 with an inclined edge cam face sloping upwardly and rearwardly and normally disposed against the front wall of the magazine. It also merges into a projecting dog or pawl 37 provided with a tooth or extension arranged to fit into the aperture 28 already referred to as being formed in the plate 23 of the blade-clamping device when the latter has been moved outwardly to its blade-releasing position. The feed slide 33 has rounded corners and a downturned flange arranged to travel in a path on the front wall of the magazine in which it engages the inclined face of the flange 36 of the locking mechanism, forcing it downwardly and retracting the dog 37 from engagement with the locking recess 28. In this movement the spring locking piece flexes about the rivet 35 as an axis.

In using the razor and magazine above described the key 38 of the magazine is first inserted in the passage 17 of the razor head and pushed fully home until the end of the magazine is arrested against upright side member 15 of the razor head. In this movement the key retracts the blade-clamping device 20-26, releasing the used blade in the blade holder and bringing the locking aperture 28 into registration with the locking dog 37 which, up to this time, has been yieldingly pressed against the portion 23 of the blade-clamping device. At the conclusion of these two movements the tooth of the dog enters the locking recess 28 and the magazine and razor head thus become positively locked against separation. Incidentally, the blade-clamping device is also positively locked by the dog 37 in its retracted or forward position. With the magazine and razor thus interlocked the user advances the feed slide 33 toward the left as seen in Fig. 2, thus feeding the uppermost blade in the stack into the blade holder of the razor head where it encounters and ejects the used blade in reaching its shaving position. As the feed slide approaches the end of its feeding movement it encounters the inclined cam surface of the flange 36 of the locking device, depresses it and causes disengagement of the dog 37 from the locking recess 28 thus freeing the magazine for separation from the razor head, but only after it has insured complete and safe delivery of the fresh blade to the razor. Disengagement of the dog 37 from the recess 28 also releases the blade-clamping device which is thereupon immediately moved rearwardly by its spring.

After the magazine has been separated from the razor the feed slide 33 is moved toward the right hand end of the magazine preparatory to engaging and feeding the next blade from the stack. In this movement the flange 36 is released and the member 34 again springs into contact with the bottom of the magazine and the dog 37 moves into operative position in readiness to

enter the recess 28 when the magazine is next presented in blade-delivering position.

Having thus disclosed my invention and described a preferred embodiment thereof in detail, I claim as new and desire to secure by Letters Patent:

1. A razor and magazine combination including a safety razor head shaped to provide a passage therein and to present a blade seat, together with a magazine having a projecting key shaped to enter the passage in the razor head and locate the magazine for blade delivery and a movable feed slide, and means for automatically locking the magazine and razor head, said locking means and feed slide having contacting surfaces whereby the locking means is released by movement of the said feed slide in the magazine.

2. A razor and magazine combination including a safety razor head having a blade seat and a spring-operated blade-clamping device, together with a magazine having a feed slide, and locking means located partly on the magazine and partly on said blade-clamping device and arranged to be retracted by movement of said feed slide in the magazine.

3. A razor and magazine combination including a safety razor head having a blade seat and an apertured blade-clamping device, together with a magazine having connecting means and a movable spring locking projection shaped to enter the aperture of the clamping device, and a feed slide movable to eject a blade from the magazine and at the same time to engage and retract the locking projection from said aperture.

4. A razor and magazine combination in which the razor has a blade seat and a transversely movable blade-clamping device, and the magazine has connecting means, a locking dog and a feed slide for delivering one blade at a time from the magazine to the razor, the blade-clamping device and the locking dog being shaped to interlock when the clamping device is retracted and to be released when the feed slide has been moved to complete delivery of a blade.

5. A razor and magazine combination in which the razor has a blade seat and a spring-operated blade clamp, and the magazine has a movable locking dog shaped to engage the blade-clamp and a movable slide for releasing said dog.

6. A razor and magazine combination in which the razor has a blade seat and an apertured blade-clamping device shaped to present a passage beneath the blade seat, and the magazine has a projecting key shaped to enter said passage and locate the magazine for blade delivery, a feed slide, and a spring dog arranged to interlock with the blade-clamping device after the latter has been retracted to release a blade in the razor, and having an inclined edge portion standing in the path of said slide.

7. A razor and magazine combination in which the razor has a blade seat and a movable blade-clamping device, and the magazine has a spring-locking element cooperating with the razor to lock the razor and magazine together and a key shaped to retract said blade-clamping device, the said locking element being shaped to engage and hold said clamping device in retracted position after it has been retracted by the key, and means for moving said locking element whereby the magazine and the clamping device are simultaneously released.

8. A razor and magazine combination comprising a razor head having therein a blade seat and a cooperating spring-actuated blade-clamping member provided with an aperture, and a magazine having a key shaped to enter the razor head and displace said blade-clamping member, a spring member on said magazine having a locking dog shaped to interlock with the aperture of said blade-clamping member after the latter has been displaced by the key, and a feed slide movable on the magazine to deliver a blade therefrom and to contact said spring member and unlock it.

JOSEPH MUROS.
